[57] CLAIM

The ornamental design for a bedpan, as shown.

DESCRIPTION

FIG. 1 is a top plan view of a bedpan embodying my design;

FIG. 2 is a section drawn substantially along the line 2—2 of FIG. 1 to aid in understanding;

FIG. 3 is a side elevational view of the bedpan of FIG. 1, the other side elevational view being identical thereto;

FIG. 4 is a rear elevational view of the bedpan of FIG. 1;

FIG. 5 is a front elevational view of the bedpan of FIG. 1; and

FIG. 6 is a bottom view of the bedpan of FIG. 1.
